UNITED STATES PATENT OFFICE.

FERDINAND F. BRUCKER, OF AKRON, OHIO, ASSIGNEE TO MILLER RUBBER COMPANY,
OF AKRON, OHIO, A CORPORATION OF OHIO.

TOY BALLOON.

1,136,932.

Specification of Letters Patent. Patented Apr. 27, 1915.

Application filed September 17, 1914. Serial No. 862,231.

To all whom it may concern:

Be it known that I, FERDINAND F. BRUCKER, a citizen of the United States, residing at Akron, in the county of Summit 5 and State of Ohio, have invented certain new and useful Improvements in Toy Balloons, of which the following is a specification.

The present invention relates to toy balloons and pertains more specifically to that type of balloons which is inflated by blowing air through a mouth-piece and can be deflated at will by allowing the air to escape from the same.

15 The principal object of the invention consists in applying to a balloon of this type an improved form of valve mechanism for maintaining the air within the balloon when the latter is in its inflated condition and also 20 for controlling the escape of the air as the balloon is deflated.

A further object consists in providing a detachable thimble shaped cup or shell adapted to be inserted and retained in the 25 mouth piece of the balloon and having at its inner end a small check valve.

With these and other objects in view, the invention consists in the construction and combination of parts more fully described 30 in the following specification and illustrated in the accompanying drawings and pointed out in the appended claims.

In the drawings: Figure 1 is a central 35 sectional view through the balloon in its inflated condition. Fig. 2 is a side elevation of the balloon deflated. Fig. 3 is an enlarged perspective view of the valve mechanism detached and, Fig. 4 is an enlarged longitudinal section of a modified 40 form of the valve mechanism. Fig. 5 is an enlarged plan view of the valve illustrated in Figs. 1 and 3.

Referring to the drawings, the balloon comprises a hollow body B of thin rubber 45 of pure quality and extreme elasticity, which will permit of its being inflated and being expanded to many times its normal size. The balloon B in its normal deflated condition is preferably of elliptical form and is 50 provided with a tubular neck or mouth-piece C extending from one end and in substantial alignment with its longer axis as shown in Fig. 2. The valve mechanism which is adapted to be inserted in the neck

piece C comprises a cup shaped member 1 55 open at its outer end and having a small valve port 2 at its inner end, adapted to be closed by a small check valve 3. The outer end of the neck piece C of the balloon is provided with a reinforcing ring c. The 60 walls of the cup shaped member 1 taper inwardly toward the inner end of the neck C.

Referring now more particularly to Figs. 1 and 3 in this form of the invention, the valve mechanism is formed of a single piece 65 of rubber comprising the cup-shaped member 1 and the check valve 3 which is virtually a small flap valve adapted to close the port 2. The cup-shaped member 1 is inserted in the mouth piece of the balloon and cemented therein. The cup member 1 can be formed of celluloid or papier-mâché or any other material sufficiently light and yet of proper stiffness to hold the mouth piece C of the balloon open. In this form of the 75 invention the inner valve port 2 of the cup shaped shell is provided with a small rubber tack valve 4 loosely held within the valve port. When the cup member is formed of this material it is not necessary to cement 80 the same in the mouth piece of the balloon for it can be easily inserted and will be retained there, the outer ring c tending to hold it against outward movement and the conical wedge-shaped formation of its walls 85 tending to hold it against inward movement.

In both forms of the invention the valve after the balloon has once been inflated is held closed by the pressure of the air within 90 and in order to deflate the balloon it is only necessary to squeeze the neck c near its inner end so as to slightly dislodge either the valve 3 or 4 as the case may be. This form of valve mechanism tends to keep the 95 walls of the mouth piece c always in a distended condition.

If anything should happen to the valve the shell could easily be removed in its entirety and replaced by a new one.

What I claim is:

1. A toy balloon having a tubular neck or mouth-piece integral therewith, a conical cup-shaped member adapted to be inserted and retained in said neck, a self-closing 105 valve formed in the inner end of said member, substantially as described.
2. A toy balloon having a tubular neck or

100

mouth-piece, a cup-shaped member having inwardly tapering walls, said member being insertible in said neck piece, a self-closing valve at the inner closed end of said member and a reinforcing ring surrounding the outer end of said neck or mouth-piece, substantially as described.

In testimony whereof I affix my signature in presence of two witnesses.

FERDINAND F. BRUCKER.
